HERSCHEL E. TOWER, OF CINCINNATI, OHIO, ASSIGNOR TO THE BALDWIN COMPANY,
OF CINCINNATI, OHIO.

EXPRESSION MECHANISM FOR MECHANICAL MUSICAL INSTRUMENTS.

Application filed March 3, 1926. Serial No. 91,982.

The expression mechanism for controlling the degree of tension in the chests of player actions that are used for operating the notes of a piano have been made of various kinds, but have all been so complicated and hard to regulate that the ordinary repair man or regulator could not regulate them. The present invention is made so simple that any one can regulate it to give the proper degrees of control and it is also made to change the degrees so quickly and with such a short motion of the governor spring that there will be no wear and no lessening of the tension of this spring by constant stretching.

A further object of my invention is to have a muffler that will allow the air to be drawn into the chests to reduce the tension and yet be quiet and will not be clogged with dust from long usage.

In the drawings Figure 1 is a front view of a mechanical musical instrument showing the pump, electric motor, expression mechanism and the player action. Figure 2 is a top view of the expression mechanism with the muffler removed. Figure 3 is a top view of the muffler showing how it is slit to break up the air currents. Figure 4 is an end view of the expression set showing how the muffler is held in place. Figure 5 is a cross section taken along line A—A of Figure 2.

A player action 1 has a roll box 2 with a tracker bar 3 for controlling the action of the pneumatics 4 as the music roll 5 is drawn forward by the air motor 6. Besides the regular note holes 7 in the tracker bar 3 there are a number of expression control holes 8, 9, 10 and 11 for controlling the action of a number of pneumatics 12, 13, 14 and a pneumatic pouch 15, which act on a reverse lever 16 that controls the action of a spring 17 which is connected to a valve rod 18 that carries a valve 19, which valve 19 is used to control the degree of air tension in the player action 1.

To create a partial vacuum in the player action 1 for actuating the pneumatics 4, and in the air motor 6 that drives the music roll 5, a pneumatic pump 20 is driven by an electric motor 21 at such speed as to give the maximum tension needed. The pneumatic pump 20 is connected to the player action 1 by a service hose 22, and to the control box 23 by a hose 24. It is also connected to the air motor 6 by a suitable hose which is not shown.

The pneumatics 12, 13, 14 on the control box 23 are each controlled by separate valves 25, 26, 27 and pouches 28, 29 and 30. The pneumatic pouch 15 is controlled by a valve 31 and a pouch 32. These pneumatics 12, 13, 14 are adapted to press down on the reverse lever 16 by means of arms 33, 34 and 35, whereas the pneumatic pouch 15 acts directly on the valve rod 18 from below and closes the valve 19.

The control valve 19 has a leather covering 36 that rests against the face of the port hole 37 so as to make a tight joint when the valve 19 is forced up into place by action of the pneumatic pouch 15. Around the valve rod 18 and resting on the center of the face of control valve 19 are a number of felt punchings 38 of different size that act inside of a felt lining 39 in the port hole 37 to break up the currents of air that go through the port hole 37 to reduce the air tension in the player action. To further reduce the noise of the air passing through the port hole 37 a cover 40 is made to fit over all the pneumatics and the control valve 19. This cover 40 is made with a plurality of long narrow slots 52 in the top that act to break up the air currents and it is also covered with a heavy layer of felt 41. For easy access to the regulating controls this cover is held in place by a pair of latches 42 that hook over pins provided on the ends of the cover.

To control the action of the pneumatics 12, 13, and 14 on the reverse lever 16, a number of stop screws 43, 44 and 45 are set in the movable leaves of these pneumatics to limit the length of the stroke. Spring 17 is set into the reverse lever and held in place by a pin 46, which pin is also used for regulating the tension of the spring 17.

The control holes, 8, 9, 10, 11 in the tracker bar 3 are connected to the pouches 28, 29, 30 and 32 by means of tubes 47, 48, 49 and 50 and the valve 31 is connected to the pneumatic pouch 15 by a tube 51.

When the electric motor 21 is started, it drives the pneumatic pump 20 causing a partial vacuum in the player action 1, control box 23 and air motor 6. If this pneumatic pump is operated fast enough to cause a vacuum of 40 inches water gauge, the notes will operate to bring out a very loud tone in the musical instrument. To vary this degree of vacuum the control valve 19 is set inside the vacuum chamber of the control

box 23 and covers the port hole 37. The effect of this vacuum is to pull the control valve 19 away from the port hole 37 allowing atmospheric air to leak in until the tension 5 of the air in the control box 23 and the player action 1 is balanced with the tension of the spring 17.

To be able to raise the tension of the air from the minimum governed by the spring 10 17, the pneumatics 12, 13, and 14 are set to pull down on the reverse lever 16, thereby increasing the tension of the spring 17 and raising the tension of the air inside the player action 1 and control box 23. The 15 minimum tension is set by the balancing of the spring 17 and the valve 19, at about 6 inches water gauge. When an opening in the music roll 5 uncovers the hole 8 in the tracker bar 3 the air is allowed to go through 20 the tube 47 and operate the pouch 28, which will then operate the valve 25, causing the pneumatic 12 to collapse until the regulating screw 43 has touched the bottom board of the pneumatic. This regulating screw 43 is 25 set so that when the arm 33 presses the reverse lever 16 down the spring 17 will be stiffened enough to raise the tension to 9 inches water gauge. When the control opening 9 is uncovered, the air operates through 30 the tube 48, pouch 29 and valve 26 to collapse the pneumatic 13 to cause the block 34 to press down the reverse lever 16 until the regulating screw 44 strikes. This screw 44 is set so that the lever can be pulled down 35 to give a tension of 12 inches water gauge. The action of the pneumatic 14 is controlled in the same manner through opening 10, tube 49, pouch 30 and valve 27. The regulating screw 45 is set so that the reverse lever 16 40 stiffens the spring 17 to give a tension of 15" water gauge.

When the control opening 11 is uncovered the air is admitted through tube 50 to pouch 32 that opens valve 31, admitting air 45 through tube 51, to the pneumatic pouch 15, which pouch 15 will be drawn up by the vacuum inside the control box 23 and press on the valve rod 18 pressing the valve 19 against the seat around the port hole 37.

50 When this valve 19 is tight against the seat

around the port hole 37 there will be no leakage and the air tension will rise in the player action and the control box 23 up to the maximum being created by the pneumatic pump 20.

As the movement of the spring 17 to change the pull on the valve 19 is very slight and due to the action of the pneumatic pouch 15 in helping to close this valve 19 at the highest tension, there is no breaking down 60 of the spring from excessive stretching.

With this action of all parts being made to move only a short distance and the ability to regulate this distance by only removing the muffler 40, the regulation can be adjusted 65 to give the exact degree very quickly, also the action of these parts when operating is so fast that the tension can be raised to the desired degree almost instantly to strike a 70 melody note and yet can drop back at once so as not to raise the tension of the accompaniment notes.

Many modifications can be made, but what I claim as my invention is:

1. In a mechanical musical instrument, a 75 pneumatic action, a power unit for creating a maximum degree of suction to actuate the said pneumatic action; an expression action comprising a relief valve, a port and a spring for controlling the suction of air created by the said power unit to a number of different degrees, the said spring so connected as to be stiffened by a number of pneumatics and separate means acting directly on said relief valve for closing off all incoming air through 80 said port.

2. In a mechanical musical instrument, a 85 pneumatic action, a power unit for creating a maximum degree of playing force to actuate the said pneumatic action; an expression action comprising a relief valve, a port and a spring for controlling the playing force created by the said power unit to a number of different degrees, the said spring so connected as to be stiffened by a number of pneumatics acting on a reverse lever, and separate means acting directly on said relief valve for moving it to a position to exclude 90 the passage of any air through said port.
